METHOD OF TREATING UNBOUND BOOKS

Carl Schramm, North Coventry, Conn., assignor
to The Smyth Manufacturing Company, Hartford, Conn., a corporation of Connecticut

Application November 16, 1937, Serial No. 174,766
Renewed May 18, 1939

10 Claims. (Cl. 11—1)

This invention relates to a treatment of stitched but unbound books preparatory to binding, which may be automatically and continuously carried on. In general it comprises feeding the books with their backs down in succession from a loading station to one or more stations where they are jogged up and down so that the folded edges of the signatures will be uniform and the book backs will be flat. The books are then passed to a press in which they are transversely compressed so as to squeeze out confined air, flatten any folds and wrinkles and compact the books to uniform thickness with their backs smooth. After being pressed the books are carried to a position in which glue is applied to the flat backs of the solidified books, and then turned flatwise, one way and the following in the opposite way, and carried to a location where they are stacked flatwise in a pile on a rack with the glued backs of the alternate books facing oppositely, that is, with the back of one book projecting on one side and the back of the following book projecting on the other side of the stack. When the required number of books are stacked on the rack the pile is deposited on a conveyor and removed for subsequent binding operations.

The subject of the invention herein set forth being a method of treatment of unbound books, only means that may be utilized for effecting the several steps of the method are illustrated,—mechanisms for connecting and synchronizing the actions of said means for taking the various steps, are not illustrated.

In the accompanying drawings Fig. 1 shows a front elevation of the essential mechanisms and means that may be employed for practicing the method.

Fig. 2 is a top plan view of what is illustrated in Fig. 1.

Fig. 3 is a transverse section of means that may be used for compressing the books.

Fig. 4 is a side view of a book at the gluing station.

Fig. 5 is an end view of a book at the gluing station.

Fig. 6 is a plan view showing a book turned flatwise one way.

Fig. 7 is a section on dotted line 7—7 on Fig. 6.

Fig. 8 is a plan view showing a following book turned flatwise in the opposite way.

Fig. 9 is a section on dotted line 9—9 on Fig. 8.

Fig. 10 is a side elevation showing the books stacked on a conveyor with their glued edges off-set.

In apparatus designed to execute the treatment, the books 1, in succession are thrust onto a trough 2 against a positioning latch 3 with their backs down. Means such as fingers 4 contact an edge of the book and feed it along the trough 5 onto means which will joggle the signatures up and down so that they will settle and the back of the book will be flat. The joggling means may be a plate 5 lifted and dropped by cam actuated levers 6 or by transversely extending eccentric 10 or flattened rapidly rotatable rolls as desired. To ensure the flatness of the back the book may then be fed by fingers 7 to a second joggling position 8, Fig. 1.

From the joggling location the book is pushed 15 by means, such as fingers 9, onto a platform 10 between a pair of press plates 11. The platform is raised by suitable mechanism, cam operated levers 12, Fig. 1, being illustrated, so as to lift the book until the press plates will cover the 20 entire surfaces of the sides of the book, and then the press plates are closed by powerful means, which may be toggles 13, Figs. 2, 3, or hydraulic, or pneumatic mechanism, so as to subject the book to a heavy squeeze. The press plates and 25 platform, box in the book and prevent any bulging of the flat back as the book is subjected to pressure, Fig. 3.

After pressing the plates are opened and the platform with the book lowered, and the pressed 30 book is pushed by suitable means, as fingers 14, into jaws 15 carried by a rotatory turret 16, Figs. 1, 2. The several feed fingers preferably engage the books near their backs, and are connected and actuated so as to be moved in, forward, outward and back coincidentally for advancing the books from station to station.

The turret shown has four radially extending arms 17 spaced 90° apart, and each arm carries a pair of jaws 15 designed to be opened and closed by appropriate mechanism, Fig. 2. The turret is mounted in a pillar 18 so it can be intermittently rotated horizontally by means engaging a gear 19 and also be intermittently reciprocated vertically by the actuation of a lever, Fig. 1.

After the turret jaws have received and clamped a book the turret is raised, rotated 90° and lowered. A set of jaws 21 then close and tightly grip the sides of the book near its back, Fig. 5. When thus positioned a flexible roll 22, carrying a suitable quantity of glue, is lifted and run lengthwise along the back of the book to apply glue thereto, and then lowered and returned, Fig. 4.

The gripping jaws are opened, and the turret, 55

carrying the book with its back glued, is raised and rotated 90°. At this time the book carrying jaws are rotated 90° transversely of the axis of the turret by means engaged with notched disks

5 23 that are mounted on the arms near the center of the turret, Figs. 1 and 2, so as to turn the book from vertical position with its back down to horizontal position with its glued back to one side. There is a set of turning means for each 10 arm, and the sets are so actuated that one pair of book carrying jaws will be turned in one direction and the following pair of book carrying jaws will be turned in the opposite direction.

When in this position the turret jaw which is 15 uppermost is raised by suitable mechanism that is actuated from pinions 24 at the center of the turret, leaving the book lying flat on the lowermost jaw, Fig. 1, the latter jaw preferably having a surface of approximately the size of the 20 book while the former jaw may be much smaller.

The lower jaw is movable transversely of the arm by which it is carried, and on its under side it has a lug 25 that, when the upper jaw is raised, is engaged by a lug 26 on a slide 27. 25 The slide is shifted by suitable mechanism, first one way then the other transversely of the arm so as to move the jaw and book first brought around by an arm a short distance to one side, Figs. 6 and 7, and move the jaw and book brought 30 around by the following arm a short distance to the other side, Figs. 8 and 9, in order that the successive books be in position to be removed and stacked with the glued backs staggered.

Gripping jaws 28, Fig. 1, then close against an 35 edge of the book and pull the book from the jaw on which it lies and deposit it on a board 29 that has been fed in from a stack 30 and laid on a rack 31, Figs. 1, 2 and 10. An endless chain 32 intermittently advanced by means 33 carries a 40 plurality of racks which are in turn brought around and pushed into position to receive the boards and books, and lowered the thickness of a book after each book is laid thereon.

When the stack reaches the predetermined 45 height the board and books are deposited on an endless chain conveyor 34 and carried away. The rack which has supported the stack is moved out and at this time a following rack has reached position to receive the books which will form the 50 next stack.

The books remain stacked on the conveyor with their glued backs 35 turned oppositely and overlying the front or cut edges 36 of the adjacent books until the glue is set or the books removed for subsequent treatment, Fig. 10.

The invention claimed is:

1. The method of treating unbound books which comprises feeding the books in succession with their backs down, joggling the books for flattening their backs by means acting against their backs, carrying the books to pressing means and compressing them over the entire surface of their sides and at the same time holding the backs from distortion, transferring the compressed books to adhesive applying means and applying adhesive to their flat backs, turning the successive books flatwise in opposite directions and stacking them on a support with the adhesive coated backs of the alternate books positioned oppositely and extending beyond the front edges of the adjacent books.

2. The method of treating unbound books 75 which comprises feeding the books in succession

with their backs down, joggling the books for flattening their backs, carrying the books to pressing means and compressing them over the entire surface of their sides and at the same time holding the backs from distortion, transferring the compressed books to adhesive applying means and applying adhesive to their flat backs, turning the successive books flatwise in opposite directions and stacking them on a support with the adhesive coated backs of the alternate books positioned oppositely and extending beyond the front edges of the adjacent books, depositing the books thus positioned onto a conveyor and removing them for further treatment.

3. The method of treating unbound books 15 which comprises feeding the books in succession with their backs down, joggling the books for flattening their backs by means acting against their backs, compressing the books transversely and at the same time holding the backs from distortion, transferring the compressed books to adhesive applying means and applying adhesive to their flat backs, turning the successive books flatwise in opposite directions and stacking them on a support with the adhesive coated backs of the 20 alternate books positioned oppositely and extending beyond the front edges of the adjacent books, depositing the books thus positioned onto a conveyor and removing them for further treatment.

4. The method of treating unbound books 25 which comprises feeding the books in succession with their backs down, joggling the books for flattening their backs, transversely compressing the books and at the same time holding the flattened backs from distortion, applying adhesive to 30 the flat backs of the books, turning the successive books flatwise in opposite directions and stacking them with the adhesive coated backs of the alternate books positioned oppositely and extending beyond the front edges of the adjacent books, and conveying the books thus positioned for further treatment.

5. The method of treating unbound books 35 which comprises feeding the books in succession with their backs down, joggling the books for flattening their backs, transversely compressing the books, applying adhesive to the flat backs of the books, and turning the successive books flatwise in opposite directions and stacking them with the adhesive coated backs of the alternate books 40 positioned oppositely and extending beyond the front edges of the adjacent books.

6. The method of treating unbound books 45 which comprises joggling the books for flattening their backs by means acting against their backs, compressing the books over the entire surface of their sides and at the same time holding the backs from distortion, applying adhesive to their flat backs, turning the successive books flatwise in opposite directions and stacking them on a support with the adhesive coated backs of the alternate books positioned oppositely and extending beyond the front edges of the adjacent books.

7. The method of treating unbound books 55 which comprises joggling the books for flattening their backs by means acting against their backs, compressing the books transversely by pressure applied to both sides and at the same time holding the backs from distortion, applying adhesive to the flat backs of the books, turning the successive books flatwise in opposite directions and stacking them on a support with the adhesive coated backs of the alternate books positioned oppositely and extending beyond the front edges of the adjacent books.

8. The method of treating unbound books which comprises feeding the books in succession with their backs down to pressing means and compacting them, transferring the compressed books to adhesive applying means and applying adhesive to their backs, turning the successive books flatwise in opposite directions, and stacking them with the adhesive coated backs of the alternate books positioned oppositely and extending beyond the front edges of the adjacent books.
9. The method of treating unbound books which comprises feeding the books in succession with their backs down to adhesive applying means and applying adhesive to their backs, turning the books flatwise in opposite directions and stacking them on a support with the adhesive coated backs

of the alternate books positioned oppositely and extending beyond the front edges of the adjacent books.

10. The method of treating unbound books which comprises feeding the books in succession with their backs down to means for joggling the books and flattening their backs, transferring the books to adhesive applying means and for applying adhesive to their flat backs, turning the successive books flatwise in opposite directions, and stacking them on a support with the glued backs of the alternate books positioned oppositely and extending beyond the front edges of the adjacent books.

CARL SCHRAMM. 15
